ATTORNEY.

UNITED STATES PATENT OFFICE.

JOSEPH W. LOVE, OF BALTIMORE, MARYLAND.

MAIL-POUCH.

SPECIFICATION forming part of Letters Patent No. 633,869, dated September 26, 1899.

Application filed July 7, 1898. Serial No. 723,014. (No model.)

To all whom it may concern:

Be it known that I, JOSEPH W. LOVE, a citizen of the United States, residing at Baltimore, in the State of Maryland, have invented 5 certain new and useful Improvements in Mail-Pouches, of which the following is a specification.

This invention relates to mail bags or pouches.

10 The object of the invention is to provide a mail bag or pouch with simple means whereby the bag may be readily and securely closed without using a strap running through staples and which is flexible when closed.

15 The invention is illustrated in the accompanying drawings, in which—

Figure 1 is a perspective view at the rear side of the mouth of the bag or pouch and shows the pouch open. Fig. 2 shows the position of the mouth parts after the first step has been taken toward closing the bag. Fig. 3 shows the position of the mouth parts when the bag is closed. Fig. 4 is a front side view of the top of the pouch, showing the flap upward. Fig. 5 is also a front side view showing the flap closed down. Fig. 6 is a horizontal cross-section of the stiffening-plates on the inside and outside of the top edge of the front wall. Fig. 7 shows a modification of the 25 stiffening-plates.

30 In the drawings, A designates the bag, b the front wall, and b' the back wall of the bag. The bag may be made of any suitable material, such as canvas or leather.

35 The front wall b has its top edge n projecting higher than the top edge o of the back wall, and the top edge of the front wall has a series of unconnected stiffening-plates c on the inside and another series c' exactly over 40 these on the outside, and the two series of plates are riveted together through the fabric of the wall of the bag. A hole d is in each of the pair of plates c c' for the purpose of conveniently hanging the bag on hooks. A horizontal cross fold or crease a occurs in the back wall just below the rows of plates c c'.

45 At the top edge of the rear or back wall b' the bag is folded back on itself at e and also has stiffening-plates f on each side of this double-thick wall, which are similar to the plates c c', and also riveted together through the double-

thick fabric. These plates f also have holes d for the purpose of inserting hooks for hanging the bag in an open position, somewhat as it appears in Fig. 1. A horizontal cross-space 55 g is left on the rear wall below the plates f and forms a crease or hinge-fold from which a flap h depends. This flap has a series of stiffening-plates i, which are without holes. The stiffening-plates c, c', f, and i are all beveled at their adjacent edges, as shown in Fig. 6, which insures flexibility between the plates.

55 Metal plates k k' on the inside and outside are riveted together through the front wall of the bag, and a staple l projects outward 60 from said metal plates. The flap h also has metal plates m m', one inside and one outside, and said metal plates have slots p, which take over the staple l when the bag is closed and the flap turned down, as in Figs. 3 and 5. 70 A suitable lock may be passed through the staple and the bag thus securely closed.

65 The operation in closing the bags is as follows: The top edge of the front wall, having the plates c c', serves as a flap which is first 75 turned down over the fold e of the back wall, as shown in Fig. 2, and then the flap h on the back is folded over the front flap, as shown in Fig. 3, and the slot p takes over the staple l. Thus the mouth of the mail-bag is securely closed. In the cross direction this closed end is flexible by reason of the unconnected plates.

70 In Fig. 7 the unconnected stiffening-plates are shown inserted in pockets formed by the 85 fabric of the pouch, and each hole has a rivet d².

Having thus described my invention, what I claim as new, and desire to secure by Letters Patent, is—

90 1. A mail-pouch having a front wall which projects higher than the back wall and provided at its top edge with a series of stiffening-plates; a back wall folded back on itself to form a double top edge and a free flap and at the double top edge provided with a series of stiffening-plates, f, which are riveted through the two thicknesses of the folded part, and a series of unconnected plates, i, on the free flap which when the bag is folded take 95 over the said stiffening-plates on the top edge of the front wall.

2. A mail-pouch having the top edge of its mouth provided at the front with an edge projecting higher than the edge of the back and serving as a flap to fold over said back edge; 5 the top edge of the back folded back on itself and terminating in a back flap, *h*, which folds forward to the front side; a row of unconnected metal plates, *c*, *c'*, on the front flap; a second cross-row of unconnected plates, *f*, on

said back edge; and a third row of unconnected plates, *i*, on the back flap which latter folds forward to the front, as set forth.

In testimony whereof I affix my signature in the presence of two witnesses.

JOSEPH W. LOVE.
